UNITED STATES PATENT OFFICE.

HERBERT HENRY BERRY, OF LONDON, AND WILLIAM JAMES MARKHAM, OF BIRMINGHAM, ENGLAND.

ELECTRIC SWITCH.

1,189,530.

Specification of Letters Patent.

Patented July 4, 1916.

Application filed November 2, 1914. Serial No. 369,977.

To all whom it may concern:

Be it known that we, HERBERT HENRY BERRY and WILLIAM JAMES MARKHAM, citizens of the United Kingdom of Great Britain and Ireland, and residents of 78 Upper Thames street, London, England, and of Suffolk Works, Oozells street, Birmingham, England, respectively, have invented certain new and useful Improvements in Electric Switches, of which the following is a specification, such as will enable others skilled in the art to which it appertains to make and use the same.

This invention relates to electric fused switches and has for its object to provide a simplified construction of quick make-and-break fused switch, which shall be strong and of durable character, and in which the parts thereof may be easily adjusted, assembled, removed and replaced.

The switch according to the invention comprises a toggle or knuckle joint, the arms of which are pivoted on a fuse cartridge which is adapted to be moved into engagement with contacts provided preferably within the switch casing. This arrangement permits of the speedy assembling of the parts during the process of manufacture; it also permits of the speedy replacement of the parts for the purpose of renewal, and has the still further advantage of providing a revolving switch contact which will lengthen the life of the switch by reason of the fact that the contact can be turned into several positions.

The invention will now be described with reference to the accompanying drawings wherein the invention is shown as applied to a double pole switch. The double pole switch has been selected for describing the invention in detail but it will be understood that the invention can also be applied to single or multiple pole switches.

Figure 1 is a section through the switch casing or box, and Fig. 2 is a plan view of the toggle mechanism of the switch.

Referring to the drawings whereon the same reference letters indicate the same or similar parts, *a* is the casing or box within which the switch is mounted. The casing may be of any convenient shape and is provided with a cover *b*. Within the casing *a* and preferably to the cover *b* is secured in any suitable manner, as by pins *d*, a bow-

shaped spring *c*, the ends *e*, *f*, of which act upon the ends *g*, *h*, of the toggle or knuckle joint.

In the preferred form of the invention for a double pole switch the joint comprises a central portion *j*, and the two end portions *k*, *l*. The central portion and preferably the two end portions, are composed of insulating material, or are insulated and are moved by any suitable means such as a rod *m* on which a knob or handle *n* is arranged. The ends of the central portion *j* are shaped into a concave groove to receive a cartridge *p*. The faces of the portions *k*, *l*, adjoining the ends of the central portion are also provided with a concave groove to engage the cartridge *p*.

The backward and forward movement of the central portion *j* causes the fuse cartridges to engage and be discharged from contacts not shown which may be fixed in the switch casing in any convenient and known manner. The cartridges act as pivots between the central portion *j* of the joint and the two end parts *k* and *l*, the grooves in the end parts *k* and *l* having a small movement on the cartridge. When it is desired to replace a cartridge fuse it is only necessary to push back the spring, which may easily be done by hand, thus releasing the cartridge and permitting it being removed and another one slipped into its place. The central portion may be constructed to carry cartridges, fuse carriers or contact bars in addition to the cartridges at its ends and thus a multiple pole switch is obtained. Generally the depth of the grooves and the pressure of the springs are sufficient to hold the fuse cartridges, against displacement, but additional means for holding or locking them more or less permanently in place may be provided if desired. The joint may be operated by means of a handle or lever passing through the side or ends of the switch case, or in any other convenient manner.

Any circular form of fuse carrier may be substituted for the fuse cartridge and a brass rod or tube may be employed instead of the fuse carrier or fuse cartridge.

What we claim and desire to secure by Letters Patent is:—

1. An electric switch comprising in combination a case, a cover therefor, a spring

- secured to said cover, a three-piece toggle joint having one end of each of the outer portions pivoted on said spring, the central portion of said joint being secured to a handle, concave portions at each end of said central portion, concave portions at one end of each of the outer portions of the joint, and a fuse cartridge between each of the adjacent concave portions on the central portion and the outer portion and adapted to be moved into engagement with contacts by said handle.
2. An electric switch having in combination a case, a cover therefor, a bow-shaped spring secured to said cover, a toggle joint having one end of each of the outer portions of the joint pivoted to said spring the other ends of said outer portions being concave, fuse cartridges between said concave portions and concave portions on the central portion of the toggle joint, and a handle for moving the joint so as to bring said cartridges into engagement with contacts.
3. An electric switch comprising in combination a case, a cover therefor, a bow-shaped spring secured to said cover, an insulated toggle joint having one end of each of the outer portions of the joint pivoted to said spring, fuse cartridges between said outer portions and the central portion of the switch, said cartridges being capable of being rotated, and a handle for moving the joint so as to bring the cartridges into engagement with contacts.
4. An electric switch comprising a three-piece toggle joint the central piece of which is secured to an operating handle and the end pieces are spring controlled, means being furnished at the adjoining ends of the central piece and the end pieces to receive a fuse cartridge which acts as a pivot between the said pieces.
5. In an electric switch a toggle joint, the parts of which have mounted upon them cartridge fuses which act as pivots between the parts, said joint having a handle by which it is operated.
6. An electric switch comprising a three-piece toggle joint the central piece of which is secured to an operating handle and the end pieces are spring controlled, means being furnished at the adjoining ends of the central piece and the end pieces to receive a fuse carrier which acts as a pivot between the said pieces.

In witness whereof we have hereunto set our hands in presence of two witnesses.
